UNITED STATES PATENT OFFICE.

FREDERIC E. GARDNER, OF BELOIT, WISCONSIN.

GRINDING MACHINE.

Application filed August 9, 1919. Serial No. 316,281.

To all whom it may concern:

Be it known that I, FREDERIC E. GARDNER, a citizen of the United States, residing at Beloit, in the county of Rock and State of Wisconsin, have invented certain new and useful Improvements in Grinding Machines, of which the following is a specification.

This invention relates to the art of grinding machines and refers more especially to machines of the type comprising two rotary grinding wheels between which articles of work to be ground are fed for grinding opposite faces of such articles.

The general object of the invention is to produce a grinding machine of very high accuracy which is automatic in its operation so that one operator can attend to several machines in operation in a shop or factory.

More particularly stated, one of the objects of the invention is to produce a grinding machine in which the grinding elements are mounted in offset or staggered relationship so that they overlap or oppose each other over only a portion of their working faces, leaving another portion of each element exposed so as to facilitate dressing the element.

Another object of the invention is to provide a novel and improved means for feeding the work between the grinding elements and further to provide for the automatic operation of the feeding means.

Another object is to effect a periodical or intermittent retracting and approaching movement of one of the grinding elements with relation to the other for the purpose of temporarily increasing the space between said elements so as to facilitate the admission of the articles of work; and in this connection it is a further object to produce a mechanism for effecting this retracting and approaching movement of said element in timed relation to the automatic work-feeding means so that the grinding elements will be separated temporarily for the admission of the successive pieces of work.

Further and ancillary objects relating to the construction and advantages of the machine will be fully set forth in the following detailed description.

Certain features of the machine disclosed herein are covered in my copending application Serial No. 472,977, filed May 27, 1921.

In the accompanying drawings, Fig. 1 is a side and Fig. 2 an end elevation of a ma-

chine embodying the principles of my invention. Fig. 3 is a plan view of the same machine. Fig. 4 is a partial side view broken away to the center line of the reciprocating carriage. Fig. 5 is a section on the line 5—5 of Fig. 4.

In the embodiment of my invention selected for illustration, a suitable base 10 carries on its opposite ends two carriages 11 and 12 equipped with grinding wheels 13 and 14 on the longitudinally extending shafts 15 and 16, driven by means of pulleys 17 and 18 from any suitable source of power (not shown). The axes of the two shafts 15 and 16 are offset out of alinement with each other as indicated in Fig. 3 so that the grinding wheels 13 and 14 only face each other over a relatively small area in the center of the machine. Between the wheels 13 and 14, there is mounted a rotatable work-carrier 19 which in the form herein shown consists of a circular disk adapted to receive small flat objects in suitable holes 20 uniformly spaced adjacent its periphery and carry them down between the grinding wheels, where they are ground, and then up to a discharge chute 27. Pieces to be ground indicated at 22 in Fig. 1 are piled in an inclined chute 23 terminating adjacent the face of the carrier 19. As the carrier rotates past the end of the chute 23 the lower-most piece will fall into the hole in the carrier and be carried down in front of the grinding wheel 13, being restrained from falling out of the hole by a suitable guide plate 24 opposite the chute 23 and an arcuate shield 25 located below said chute opposite the wheel 14. As the piece of work is carried down between the opposed faces of the grinding elements by the rotation of the carrier, the carriage 11 is automatically drawn back to let the piece of work enter freely. After the work is entirely between the opposed portions of the faces of the grinding wheels, the carriage 11 is automatically fed in and the piece is ground to an exact thickness. The carriage is then drawn back again and the finished piece is carried up across the face of the wheel 13, being restrained from falling out of its hole by a suitable arcuate shield 26 until it reaches the discharge chute 27 into which it falls and by which is conveyed to a suitable receptacle (not shown). The finished piece moves out and a new piece is moved in at each retraction of the carriage 11.

The automatic means for rotating the carrier 19 and reciprocating the carriage 11 will next be described. A drive shaft 28 carrying a cone of pulleys 29 is driven by 5 any suitable source of power (not shown). A worm 30 on the drive shaft 28 engages a worm wheel 31 on a vertical shaft 32 mounted in stationary bearings in the base and carrying at its upper end a cam or eccentric 33. The carriage 11 is slidably mounted on ways 34 on the sub-base 35 which is pressed toward the work by a powerful coil spring 36 compressed between the 10 end of the carriage and an adjustable butt-plate 37 carried by the set screw 38 in a suitable bracket 39 projecting from the base 10.

A pin 40 in the floor of the sub-base 35 carries a roller 41 adapted to be engaged by 20 the eccentric or cam 33 whereby the sub-base and carriage may be forced away from the work. To secure greater accuracy in allowing the sub-base to move forward under the force of the spring 36 to a certain 25 point than can be secured by a roller such as 41 which is subject to considerable wear, I provide a stop bar 42 notched into the ways 43 on which the sub-base 35 slides on the base 10, and suitably fastened in place 30 as by screws 44. One face of the bar 42 abuts against the outer side of the channel 44^a in the floor of the sub-base 35 to limit the motion of the sub-base toward the work. It will be seen that these surfaces have no 35 sliding motion but are merely laid face to face against each other and separated again by the action of the cam. The wear on them is therefore inappreciable and a very high degree of accuracy in the motion of 40 the sub-base and carriage can be secured.

For operating the carrier 19 in synchronism with the reciprocation of the carriage 11 so that the carriage will be moved outward each time a piece of work is to be fed 45 between the opposed portions of the faces of the grinding element, a pair of bevel gears 45 drive the horizontal shaft 46 from the vertical shaft 32. Spur gears 47 and 48 drive a second horizontal shaft 49 extending 50 along the center line of the machine and at its inner end carrying a drive disk 50. The two disks 50 and 19 have intermeshing gear teeth so that the carrier 19 is driven by the power disk 50. These disks must obviously 55 be of less thickness than the thickness of the work being ground. Their intermeshing teeth engage each other just below the piece of work while it is being ground and are exposed to the grit and dirt produced by 60 the grinding operation. The carrier 19 is journaled in alined bearings 51 and 52 carried by upstanding arms 53 and 54 each arm offset as shown to clear the adjacent grinding wheel. To prevent particles of 65 grit or other obstacles from breaking some

part of the machine, the journals 51 and 52 are vertically slotted allowing a very slight vertical motion of the work carrier. The grinding wheels 13 and 14 are rotated so as to press down upon the work they are 70 grinding and this pressure as well as the weight of the carrier 19 is carried by the drive disk 50. The upper journals 51 and 52 merely maintain the axis of the carrier 75 exactly in the vertical central plane of the machine and approximately horizontal.

The movement of the reciprocating sub-base 35 and carriage 11 is guided by the ways 34 and 43, and their alinement on the base 10 can not be changed after the machine 80 has been assembled. Means are provided for securing perfect parallelism of the axes of the two grinding wheels by adjustment of the second carriage 12. A knee 53 is journaled on a horizontal axis at 54 on the 85 base of the machine and supported at its outer end at 55 by a threaded rod 56 and an adjusting nut engaging a suitable surface on the base. A sub-base 53' is adapted to be clamped in position on the knee 53 by 90 four bolts 57, 58, 59 and 60 passing through alined lugs on the sub-base and the knee respectively. The lugs for the bolt 60 have round holes fitting the bolt whereas one of the lugs for each of the other bolts 57, 58 95 and 59 has an arcuate slot to allow a small amount of rotation of the entire sub-base 12 around the bolt 60 as a center. Suitable upstanding lugs 61 and 62 on either side of the knee 53 carry adjusting bolts 63 by 100 means of which when the main bolts 57, 58, 59 and 60 are loosened, the sub-base 53' can be conveniently and accurately adjusted in the exact alinement in the horizontal plane. It will be seen that these two adjustments 105 completely provide for perfect alinement of the two grinding elements.

For adjusting one or both of the grinding elements 13 and 14 with respect to the work, each carriage 11 and 12 is slidably mounted 110 with respect to its sub-base 35 and 53' respectively, by ways 34 and 64. The means for making this adjustment comprises in each instance a nut 65 (see Fig. 4) embodying a worm wheel 66 meshing with a transverse 115 worm 67 and engaged between opposed faces of the carriage 11 or 12 carrying the grinding element. A screw-threaded shaft 68 passes through the nut 65 in suitable engagement therewith and is restrained from axial 120 movement by suitable collars 69 engaging an upstanding lug 70 on the sub-base. For quick adjustment of the grinding element, the shaft 68 is rotated within the nut by means of a handle 71. A slower and much 125 more accurate adjustment is obtainable by clamping the shaft by means of the clamping bolt 72 and rotating the nut by means of the transverse worm 67 which projects laterally from the carriage 11 or 12 and bears 130

a suitable knurled hand wheel 73. In changing from one size of work to another it is convenient to use the quick adjustment for an approximate setting of the machine after which it may be tightened and exact adjustment as well as readjustment whenever necessary to compensate for the wear of the grinding element may be obtained by means of the hand wheel 73.

10 For work of the highest degree of accuracy, frequent or sometimes practically continuous dressing of the grinding element may be necessary. The offset arrangement of the grinding wheels is peculiarly advantageous in that it permits such a dressing operation to be performed by a simple attachment at any time without disturbing the operation or adjustment of the machine as a whole. Referring to Figs. 1 and 2, the sub-base 35 has an integrally formed extension 74 laterally offset and extending past the grinding element 13. A suitable frame 75 bolted on the extension 74 carries a dressing device which may be of any desired form. I have illustrated a transversely slidable member 76 actuated by a suitable hand wheel 77 adapted to carry a dressing tool past the face of the grinding element. The common type of diamond dressing tool may be mounted in the bore 78 for adjustment toward and away from the grinding element. The sub-base 53' has a duplicate extension 79 and dressing device which need not be further described in detail. It will be seen that the dressing tools may operate on the outer side of the grinding elements to effectively dress the entire working surface thereof at any time. This might be done simultaneously with the operation of the machine to grind a piece of work.

The device I have disclosed is very efficient, turning out large numbers of duplicate machine parts with a very high degree of accuracy and uniformity. It embodies all the necessary adjustments to maintain this accuracy and uniformity in spite of wear due to use. It will operate entirely automatically as long as a supply of material is kept in the feed chute, so that the continuous attention of the operator is not essential.

While I have shown and described in detail the embodiment of my invention at present preferred it should be understood that the description is only for purposes of illustration and that many modifications and variations will naturally occur to those skilled in the art. I aim in the subjoined claims to cover all such legitimate modifications and variations.

I claim as my invention:

1. In a grinding machine, in combination, a frame, a grinding element rotatable on an axis extending longitudinally of said frame and offset from the center line thereof, a standard on said frame beside said grinding

element extending up and over said element to support a bearing over the center line of the machine, a second grinding element rotatable on an axis offset on the other side of the center line of the machine from said first grinding element, a second standard extending upwardly beside said second grinding element and over the same to support a second bearing over the center line of the machine, and a rotatable carrier mounted in said bearings adapted to support a piece of work and by its rotation to carry said piece of work past the center line of the machine between the opposed portions of the faces of said grinding elements. 70

2. In a grinding machine, in combination, opposed grinding elements rotatable on parallel off-set axes whereby a portion only of the face of each element is opposed to a corresponding portion of the face of the other element, a disk rotatable on an axis parallel to the axis of rotation of said grinding elements and adapted by its rotation to carry a piece of work between the opposed portions of the faces of said grinding elements, and a drive disk engaging the lower portion of the periphery of said first mentioned disk and adapted to rotate said disk and also support the weight thereof. 80

3. The combination recited in claim 2 in combination with bearings for said upper disk, said bearings being slotted vertically to allow said disk to rise slightly whereby its weight may be carried on the drive disk and whereby obstructions caught between the interengaging faces of said disks will raise said upper disk rather than break the machine. 95

4. A grinding machine having, in combination, a base, two sub-bases carried by said base offset in opposite directions from the longitudinal axis of said base, a longitudinally slidable carriage on each sub-base, rotatable grinding elements supported by said carriages and opposing each other centrally of the machine, manual means for adjusting the longitudinal position of each carriage with respect to its sub-base, power means for reciprocating one of said sub-bases and means for adjusting the alinement of the other sub-base by rotation independently about each of two mutually perpendicular axes. 110

5. A grinding machine having, in combination, a base, two sub-bases carried by said base and offset in opposite directions from the longitudinal axis of said base, a longitudinally slidable carriage on each sub-base, rotatable grinding elements supported by said carriages and opposing each other centrally of the machine, a standard opposite each grinding element extending upwardly in front of the other grinding element and inwardly to the center line of the machine to carry a rotatable work carrier 120

having a portion of its periphery passing between opposed portions of said grinding elements.

6. The combination recited in claim 5 in combination with a drive disk engaging the lower portion of the periphery of said work carrier and adapted to rotate said work carrier and also to support the weight thereof.

7. The combination recited in claim 6 in combination with slotted bearings for said work carrier whereby said carrier may be allowed to rest upon said drive disk.

8. In a machine of the class described, the combination of a work holder, a main base on which said work holder is supported, a sub-base slidable on said main base, a carriage shiftable on said sub-base, a grinding wheel structure journaled on said carriage to co-operate with the work holder to grind work, cam mechanism engaging directly with said sub-base to shift it away from the work holder, a spring for resisting outward movement of said base and for returning said sub-base inwardly when released from said cam mechanism, and a stop for limiting the inward movement of said sub-base.

9. In a grinding machine of the class described, the combination of a main base, a work holder supported on said main base, a sub-base shiftable on said main base, a carriage structure shiftable on said sub-base, a grinding wheel structure journaled on said carriage to be bodily shifted therewith toward and away from said work holder as said sub-base is shifted, a cam roller on said sub-base, a cam engaging with said cam roller to shift said sub-base away from the work holder, a compression spring resisting such movement of the sub-base and serving to return said sub-base after release thereof from said cam whereby work on the work holder will be applied under spring pressure against said grinding wheel.

10. In a grinding machine of the class described, the combination of a main base, carriage structures mounted on the opposite ends of said main base, grinding elements supported on said carriage structure for rotation, a revolvable work holder between said grinding elements having a plurality of

work receiving openings, a standard on each side of said work holder supported on the main base, a shaft journaled in the upper ends of said standards for supporting said work holder between them, a feed chute supported on one of said standards for feeding articles into the work holder opening, and a chute supported on the other standard for receiving and discharging the ground articles.

11. In a grinding machine of the class described, the combination of a main base, carriage structures adjustably mounted on said main base, grinding elements rotatably supported on said carriage structures and opposed to each other, a revolvable work holder between said grinding elements, a standard on each side of said work holder supported on said main base, a shaft journaled in the upper ends of said standards to which said work holder is secured, said work holder having a plurality of work receiving openings, a feed chute mounted on one of said standards for feeding articles to be ground into the work holder openings as said work holder revolves, a guide plate on the other standard for holding articles in the work holder openings, and a discharge chute on said other standard for receiving and discharging ground articles.

12. A grinding machine having, in combination, a base, a sub-base slidably mounted on said base, a rotatable grinding element supported on said sub-base, a second grinding element mounted opposite said first mentioned element, a carrier for moving work between said grinding elements at regular intervals, a cam roller mounted on said sub-base, a shaft journalled in said base and having a cam which engages said cam roller, a horizontal shaft for driving the carrier said horizontal shaft being geared to said first mentioned shaft, and power means for driving said first mentioned shaft whereby a rotation of the carrier and a reciprocation of the first mentioned grinding element in timed relation is effected.

In testimony whereof, I have hereunto set my hand.

FREDERIC E. GARDNER.
